Primary Examiner — David G Muller*Assistant Examiner* — Nathan M Johnston(74) *Attorney, Agent, or Firm* — Alston & Bird LLP(57) **CLAIM**

The ornamental design for an air freshener, as shown and described.

DESCRIPTION

FIG. 1 is a top perspective view of an air freshener showing our new design.

FIG. 2 is a front view the air freshener of FIG. 1.

FIG. 3 is a back view of the air freshener of FIG. 1.

FIG. 4 is a left side view of the air freshener of FIG. 1.

FIG. 5 is a right side view of the air freshener of FIG. 1.

FIG. 6 is a top view of the air freshener of FIG. 1.

FIG. 7 is a bottom view of the air freshener of FIG. 1; and, FIG. 8 is a bottom rear perspective view of the air freshener of FIG. 1.

The broken lines shown are provided for the purpose of illustrating environmental structure and form no part of the claimed design.

1 Claim, 8 Drawing Sheets---
